UNITED STATES PATENT OFFICE.

CHARLES ALGERNON PARSONS, OF NEWCASTLE-UPON-TYNE, ENGLAND.

MARINE STEAM-TURBINE.

SPECIFICATION forming part of Letters Patent No. 769,272, dated September 6, 1904.

Application filed June 27, 1902, Serial No. 113,501. (No model.)

To all whom it may concern:

Be it known that I, CHARLES ALGERNON PARSONS, engineer, a subject of the King of Great Britain and Ireland, residing at Heaton Works, Newcastle-upon-Tyne, in the county of Northumberland, England, have invented certain new and useful Improvements in Marine Steam-Turbines, (for which I have made application for Letters Patent in Great Britain, No. 24,515, dated December 2, 1901; in France, No. 317,003, dated December 18, 1901; in Germany, application filed December 19, 1901, and in Austria, application filed December 21, 1901,) of which the following is a specification.

My present invention consists in certain arrangements and combinations of steam-turbines to secure a higher degree of economy when running at reduced or cruising speeds.

In the specification accompanying my application, Serial No. 45,163, filed January 28, 1901, I described a combination of one or more reciprocating engines with steam-turbines for dealing economically with the steam when the propelling-engines are running at very low rates of speed and correspondingly very reduced horse-powers. The present arrangement, however, is for obtaining economies at cruising speeds, which are often above the limits of rotational speeds at which reciprocating engines can safely be worked for long periods of time.

My invention is intended to provide a combination of cruising and full-power steam-turbines and is an improvement upon the invention which forms the subject of the above-mentioned application, Serial No. 45,163. It is also an improvement upon the patent already granted to me, No. 608,969, dated August 9, 1898.

To carry out the invention in warships—such as battle-ships, cruisers, or torpedo-boat destroyers—the main turbines consist of one high and two low pressure turbines driving separate shafts. The low-pressure turbines are coupled to two cruising-speed turbines secured to prolongations of the main low-pressure-turbine shafts and carry small and numerous rows of blades. These cruising-turbines consist of a high-pressure turbine and an intermediate-pressure turbine. They are

of such capacity that they can only pass the comparatively small volume of steam required for cruising purposes. When cruising at the lower rates of speed, the steam from the boiler passes successively through the high-pressure turbine and the intermediate-pressure cruising-turbines and thence to the main high-pressure turbine and on through the two low-pressure turbines to the condensers, thus securing a very high degree of expansion of steam and high coefficients of efficiency in the turbines when they are running at reduced speeds. When higher speeds are required, a portion or the whole of the boiler-steam is admitted to the intermediate-pressure cruising-turbine and then passed, as before, into the main turbines. Under the latter condition I prefer to run the high-pressure cruising-turbine idly, a backflow of steam from the intermediate-pressure cruising-turbine into the high-pressure turbine being prevented by a non-return valve in the pipe which connects these two turbines. In order that the high-pressure turbine shall then revolve with very little resistance, I may place it in direct valve-controlled communication with the condenser. It will then run idly in the condenser-vacuum. The non-return valve above referred to may be, however, dispensed with and the high-pressure cruising-turbine run idly in high-pressure steam; but as this turbine is relatively small its resistance is inconsiderable. Still higher rates of cruising speed can be obtained by admitting additional boiler-steam into the main high-pressure and low-pressure turbines. It is desirable to interpose non-return valves between all the turbines to prevent a backflow of steam into the higher-pressure turbines when steam at boiler-pressure is admitted directly to the main turbines. For obtaining intermediate grades of speed between those above mentioned I may provide the high and intermediate cruising turbines with steam-inlets at intermediate positions in their lengths. The cruising-turbines are perfectly steam-balanced in themselves and are coupled to the low-pressure turbine-shafts by any suitable coupling, either fixed or detachable.

Referring now to the accompanying draw-
100

ings, Figure 1 is a plan of the turbine arrangement, the piping being shown diagrammatically only. Fig. 2 is an elevation of a portion of the piping to the high-pressure 5 cruising-turbine. Fig. 3 is a sectional view of the non-return valve drawn to an enlarged scale.

The main turbine set consists of a high-pressure turbine *a*, mounted upon the central 10 shaft *y*, and two low-pressure turbines *b* and *c*, mounted upon shafts *x* and *z*, respectively. The shafts *x* and *z* are extended forward of the low-pressure turbines and have mounted upon them the cruising-speed turbines *d* and 15 *e*, of which the former is the high-pressure turbine and the latter the intermediate-pressure turbine. The turbines *d* and *e* have small and numerous rows of blades and are of such capacity that they can only deal with the 20 comparatively small volume of steam required for cruising purposes. When it is desired to propel the vessel at low rates of speed, steam from the main steam-pipe *f* passes by way of the stop-valve *h*, the branch pipe *j*, pipe *i*, 25 *T*-piece *k*, valve *m*, (see Fig. 2,) and pipe *n* to the high-pressure turbine *d*. After passing through this turbine the steam flows through the pipe *o* to the intermediate turbine *e*, thence by pipe *p* to the main high- 30 pressure turbine *a*, and thence by pipes *q* *q* to the low-pressure turbines *b* and *c* and by way of the exhaust-bends *r* *r* into the condensers *s* *s*. The steam thus passes through all the 35 turbines in series into the condenser, and thereby secures a very high degree of expansion of steam and high coefficient of efficiency in the turbines when they are running at slow speeds. It will be seen that this follows from introducing a much larger number of steps 40 by employing additional turbines. When a somewhat-increased rate of speed is required, additional steam at boiler-pressure may be admitted to the high-pressure turbine *d* at a point intermediate in its length by way of the 45 valve *t* and steam-pipe *u*. When higher rates of speed than those above referred are required, a portion or the whole of the boiler-steam is admitted to the intermediate turbine *e* by the steam-pipe *v*, *T*-piece *w*, and pipe *z*. In this 50 case I may run the turbine *d* idly in the high-pressure steam communicated to it from the turbine *e* through the pipe *o*; but I prefer to place a non-return valve *3* in the pipe *o* to prevent backflow of steam into the high-pressure 55 turbine. This valve is hereinafter described in detail with reference to Fig. 3 of the drawings. As the high-pressure turbine is relatively small, its resistance to rotation in high-pressure steam is inconsiderable. In some 60 cases, however, I connect it directly with the condenser by means of a suitable valve-controlled pipe, (not shown in the drawings,) so that it may rotate idly in the condenser-vacuum. The turbine *e* may also be provided 65 with an intermediate live-steam admission-

pipe 4 and valve 5 for the same purpose as the pipe *u* and valve *t*. The shafts to which the turbines *d* and *e* are secured may be detachably coupled to the shafts *x* and *z*, so that the turbines may be stopped, if desired, when the main turbines alone are in operation. Still higher rates of speed can be obtained by admitting steam direct from the boiler to the main high-pressure turbine *a*. This may be effected by means of the branch pipe *j*, stop-valve 7, breeches-pipe 8, and the two steam-pipes 9 9. To prevent a backflow of steam from the main high-pressure turbine *a* into the intermediate-pressure turbine *e*, a non-return valve 11, similar in construction to but larger than the valve 3, is interposed in the pipe *p*. 70 75 80

In some cases where even higher rates of speed than above referred to are desired I supply steam at boiler-pressure to the main low-pressure turbines by the valve-controlled pipes 12 12, and I employ non-return valves 13 13 in the pipes *q* *q* to prevent a backflow of steam into the main high-pressure turbine. 85

The turbine and piping arrangements are 90 only shown diagrammatically in Fig. 1, and the arrangement for reversing the turbines and operating auxiliary machinery, which form no part of the present invention, are omitted, so that the drawing may be more 95 clearly understood.

When the turbine set consists of high-pressure, intermediate-pressure, and low-pressure turbines on three shafts, as used on the *Turbinia* and described in the specification accompanying my Serial No. 620,719, filed January 26, 1897, the additional turbine set consists, preferably, of one cruising-turbine only, 100 with a non-return valve in the piping which connects the turbine in series with the turbines of the main set. The turbine which comprises the additional set is conveniently mounted upon an extension of the center low-pressure-turbine shaft. 105

Although I have only mentioned two cruising-turbines in the case illustrated in Fig. 1, I do not limit the number to two. Larger numbers of cruising-turbines and different arrangements and graduations may be used, according to the circumstances of the case, so long as these turbines are additional to the 115 turbine sets forming the main engines and are of capacity adapted to cut down the steam used to that required for cruising purposes.

The non-return valve 3, hereinbefore referred to, is illustrated in Fig. 3. The flanged neck 16 of the valve-chest opens toward the high-pressure turbine *d*, and the neck 17 opens toward the intermediate-pressure turbine *e*. When the pressure of the steam at the exhaust end of the turbine *d* is greater than that at the inlet end of the turbine *e*, it lifts the valve against the tension of a very light spring 15, attached to the end of a pivoted valve-lever 14, thereby enabling a flow of steam to 120 125 130

take place from the high-pressure turbine to the intermediate-pressure turbine. When, however, steam direct from the boiler is admitted to the intermediate-pressure turbine, the pressure of steam there will be in excess of the exhaust-pressure of the high-pressure turbine, and the valve 3 will automatically close and prevent a backflow of steam to the high-pressure turbine. The other non-return valves 11, 13, and 13 are of the same construction as and they operate in a similar manner to the valve 3. Expansion-joints 18 may be provided between the non-return valves and the turbines, as seen in Fig. 1.

Having now described my invention, what I claim as new, and desire to secure by Letters Patent, is—

1. A system of turbines for propelling vessels consisting of a main turbine set for propelling the vessel with high economy at fast speeds, and an additional turbine set adapted to be put in series with the main turbine set when the vessel is to be propelled with high economy at cruising and low speeds, and automatic means for preventing a backflow of steam from the main turbine set to the additional turbine set when the former set is propelling the vessel at fast speed, substantially as described.
2. A system of turbines for propelling vessels, consisting of a main turbine set for propelling the vessel with high economy at fast speeds and an additional turbine set adapted to be put in series with the main turbine set for propelling the vessel with high economy at cruising and slow speeds, the former set comprising a plurality of turbines of large capacity mounted upon a corresponding number of propeller-shafts, and the latter set comprising a plurality of turbines of relatively small capacity mounted upon extensions of the propeller-shafts, substantially as set forth.
3. A system of turbines for propelling vessels, consisting of a main turbine set for propelling the vessel with high economy at fast speeds and an additional turbine set adapted to be put in series with the main turbine set

for propelling the vessel with high economy at cruising and slow speeds, the main set comprising a high-pressure and two low-pressure turbines of large capacity mounted upon separate propeller-shafts, and the additional set comprising a high-pressure turbine and an intermediate-pressure turbine mounted upon extensions of the propeller-shafts, substantially as set forth.

4. A system of turbines for propelling vessels, consisting of a main turbine set for propelling the vessel with high economy at fast speeds and an additional turbine set, for propelling the vessel with high economy at cruising and slow speeds, the main set comprising a high-pressure and two low-pressure turbines of large capacity, and the additional set comprising a high-pressure turbine and an intermediate-pressure turbine, piping connecting the additional turbine in series with the main turbine set, non-return valves in said piping between the turbines, and valve-controlled live-steam inlets to each turbine of both sets, substantially as set forth.

5. A system of turbines for propelling vessels, consisting of a main turbine set for propelling the vessel with high economy at fast speeds and an additional turbine set for propelling the vessel with high economy at cruising and slow speeds, the main set comprising a plurality of turbines of large capacity and the additional set comprising a plurality of turbines of relatively small capacity, piping putting the cruising-turbines in series with the main turbines, non-return valves in this piping between the turbines of both sets, valve-controlled live-steam inlets to each turbine, and additional live-steam inlets situated at intermediate positions in the lengths of the turbines of the cruising set, substantially as set forth.

In witness whereof I have hereunto set my hand in presence of two witnesses.

CHARLES ALGERNON PARSONS.
